STOP MECHANISM FOR TOWEL DISPENSERS

Joseph L. Zizzi, Utica, N. Y., assignor to
Joseph Darman, Utica, N. Y.

Application June 22, 1954, Serial No. 438,389

8 Claims. (Cl. 312—38)

This invention relates generally to towel dispensing units of the type for dispensing a continuous loop of toweling and has for its primary object the provision of improvement in the stop mechanism.

Another object of this invention is to provide an improved stop mechanism and dispensing unit for continuous loop towel cabinets which embody the provision of a rigid, self-contained and removable dispensing unit assembly which may be easily removed from or replaced in the dispensing cabinet.

A further object of this invention is to provide an improved continuous loop towel dispensing mechanism in which are provided a pair of spaced side wall members rigidly interconnected at three spaced points thereon by assemblages which perform functions other than the interconnecting of the side walls.

Still another object of this invention is to provide an improvement in the stop mechanism of a dispensing towel cabinet assembly which involves the use of a helical cam member and associated radial abutment member which make possible the mounting of a dashpot mechanism in an easily accessible yet out of the way position which does not detract from the space available for the operation and positioning of other mechanisms in the dispensing unit.

Another object and feature of this invention is the provision of an improved stop mechanism which includes a helical cam and a radial abutment member, the abutment member serving not only to periodically arrest dispensing movement of the internal part of the unit but also to properly reposition one of the working parts thereof.

Still another object of this invention is to provide improvements in the stop mechanism of a towel dispensing unit which includes a fixed smoothing plate serving in part to rigidify the side walls of the unit and a movable smoothing plate mounted for positioning toward and away from the fixed smoothing plate, the stop mechanism including a radical abutment member serving to periodically arrest concentric movement of the internal part of the unit and also to assure the positioning of the movable smoothing plate in a position closely adjacent to the fixed smoothing plate.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a vertical section taken through the towel dispensing cabinet showing the improved dispensing unit mounted therein;

Figure 2 is a horizontal section taken substantially along the plane of section line 2—2 in Figure 1;

Figure 3 is a vertical section taken substantially along the plane of section line 3—3 of Figure 2;

2

Figure 4 is a vertical section taken substantially along the plane of section line 4—4 in Figure 2;

Figure 5 is a horizontal sectional view looking upwardly within the dispensing cabinet and showing the dispensing unit in bottom plan;

Figure 6 is a horizontal sectional view showing details of the stop mechanism;

Figure 7 is an end elevational view of the dispensing unit;

10 Figure 8 is a perspective view of the combined cam and abutment member;

Figure 9 is a perspective view of the actuating lever;

Figure 10 is an enlarged longitudinal section taken substantially along the plane of section line 10—10 in Figure 5 and showing the details of the internal construction of the dashpot mechanism;

15 Figure 11 is a diagrammatic sectional view showing the cam mechanism in one position of rotation and relating the free end of the actuating arm with respect thereto; and

20 Figure 12 is a view similar to Figure 11 but showing the actuating arm in engagement with the abutment member.

25 Referring now more particularly to the drawings, and most specifically at this point to Figure 1, reference numeral 10 indicates a dispensing cabinet assembly generally which includes the rear wall member 12, the side wall members 14 and a horizontal shelf 16 extending between and rigidly interconnecting the side walls 14.

30 The improved dispensing unit is indicated generally by the reference character 18 and includes a pair of spaced side wall members 20 and 22 (see Figure 2) which are rigidly interconnected at three spaced points by a mounting bar member 24, a fixed smoothing plate 26 and a

35 supporting bar 28.

As shown most clearly in Figure 4, the fixed smoothing plate 26 is provided at its opposite ends with mounting tab portions 30 which receive therethrough the fastening elements 32 by means of which the plate is fastened to

40 and is rigidly interconnected to the side walls 20 and 22.

As will be seen most readily in Figure 2 and 3, both the mounting bar 24 and the support bar 28 are provided with reduced end portions 34 and 36 respectively which are threaded and which project through the side wall

45 members 20 and 22 and are provided thereon with the nut members 38 and 40.

Suffice it to say at this point that the three members 24, 26 and 28 present the sole means for rigidly interconnecting the side walls 20 and 22 although, as will be presently apparent, these members serve not only the interconnecting function but also other and important functions as well. Although the other functions are not as yet set forth, it is well to note that the dual purposes of the elements 24, 26 and 28 form an important part of this invention since they serve, by their dual purpose functioning, to reduce the over-all number of parts required, present a neat and compact unit and one which is extremely durable, rigid and economical in manufacture.

50 The side wall members 20 and 22 are provided with aligned pairs of bushing members 42 and 44 which rotatably receive axle members 46 and 48 of a feed roll member 50 and a take-up roll member 52 respectively. The axle members 46 and 48 project through the side wall 20 and are provided adjacent the outer surface thereof with a pair of sprocket members 54 and 56 which receive an endless flexible chain element 58 therearound such

55 that common and length rotation is imparted between the two roll members. Rigidly affixed to the opposite end of the axle or journal shaft 46 adjacent the inner surface of the side wall 22 is a cam element indicated generally by the reference character 60 which includes a generally

60

65

70

semicircular helical cam portion 62 having a helical cam base or surface 64 thereon formed on one side thereof and a radially projecting abutment member 66. A bracket member 68 is rigidly mounted on the inner face of the wall 22 as by a plurality of rivets 70 or the like and this bracket includes a pair of spaced parallel ear members 72 and 74 receiving a pivot pin 76 through their apertures by means of which an actuating lever member 78 is pivotally secured therebetween. It will be noted that the pin 76 is provided with a flat end portion 80 which, through its being flat, is too large to pass through the apertured ears 72 and 74 and which, by virtue of the bolt member 82 extending through a flange 84 of the mounting bracket and held thereon as by a nut member 86, is prevented from being withdrawn from the bracket ears 72 and 74 since the inner or free end of the bolt 82 contacts one of the flat surfaces of the flat portion 80.

As seen most clearly in Figure 9, the actuating lever 78 includes a main strap or body portion 88 which has one free end portion 90 adapted to be disposed in the path of movement of the helical cam surface 64 and which has secured to one side thereof a strip of material 92 deformed in a portion 94 thereof to receive between the strap 88 and the deformed portion the pivot pin 76 and which presents at the opposite end of the strap portion 88 a mounting yoke assembly 96. The yoke 96 includes a lower flange portion 98 having a pivot stud 100 mounted thereon and also includes retaining flange portion 102 overlying the flange 98.

The manner of interconnection between the strap 88 and the member 92 is by suitable fastening means such as the rivet 104, or the like.

As seen most clearly in Figure 5, a dashpot assembly is indicated generally by the reference character 106 and mounted by suitable mechanism hereinafter described to the forward face of the fixed smoothing plate member 26, the bottom flange portion thereof being indicated by the reference character 108, and this dashpot or retarding mechanism includes a piston rod member 110 having a flattened end portion 112 provided with an aperture receiving the stud member 100 on the lower flange 98 of the yoke assembly 96.

As seen most clearly in Figure 10, the dashpot assembly 106 embodies a cylindrical casing member 114 closed at its opposite end by the cap members 116 and 118, the former of which is provided with a central aperture through which the piston rod 110 projects. The inner end of the piston rod is provided with a reduced threaded end portion 120 which carries a resilient cup member 122 backed on opposite sides with the rigid washer members 124 and 126 which are held thereagainst under action of the nut member 128 and it is to be noted that the coil spring 130 is disposed concentrically of the piston rod 110 between the washer 124 and the end cap 116 to normally position the cup 122 adjacent the end cap 118. Thus, the action of the coil spring 130 also serves to position the actuating lever 78 such that its free end 90 is disposed just in the path of movement of the smaller end of the helical cam portion 62.

Rotary movement of the roll 50 and consequently the cam element 60 will pivot the actuating lever 78, by virtue of the configuration of the cam base 64, in a direction such as to withdraw the pitman rod 110 and draw air into the interior of the cylinder 114 through the bleed opening 132 in the end cap 118.

The bleed opening 132 is partially threaded from its open end as indicated by the reference character 134 and received therein is one end of the threaded adjusting bolt member 136 which is provided with a longitudinal slot 138 so as not to completely block the bleed opening 132. The bolt 136 is provided with an enlarged narrow head portion 140 preventing a shoulder engaging against a resilient valve member 142 surrounding the bolt 136 and

presented with the diametrically extending groove 144 in its end spooe which abuts the outer face of the end cap 118. The valve member 142, being resilient, is deformed by manipulation of the bolt member 136 such as to present a greater or lesser opening through the groove 144 and consequently vary the timing action of the dashpot 106.

In this respect, attention is directed most particularly at this point to Figures 11 and 12 wherein certain relative positions between the free end 90 of the actuating arm, the cam 62 and the abutment member 66 are shown. In Figure 11, the roll 50 is at that point of rotation wherein the end 90 of the actuating arm is just about to be disengaged from the wider end portion of the helical cam 62 and in Figure 12 the end portion 90 of the actuating arm is shown in engagement with the abutment member 66, which operation prevents further movement of the roll 50, as will be readily apparent. Figure 12 also shows clearly the relationship between the forward and wider ends of the cam as well as the relationship of the cam surface 64 relative thereto.

When the piston rod 110 has been completely withdrawn, and the end 90 of the actuating arm or lever is disengaged by the cam 62, the tension of the coil spring 130 will tend to return the piston and consequently the actuating arm to their normal positions. However, a certain interval of time elapses between the time the arm portion 90 is released and the time that the arm portion 90 is returned to its normal position inasmuch as the dashpot assembly will retard this action, depending upon the presetting of the adjustable bleed valve mechanism. During the short period of time, the actuating lever free end portion 90 will be disposed in the path of movement of the abutment member 66 and will of course prevent further rotation of either of the rolls 50 or 52.

As is more or less conventional, the rotation of the rolls 50 and 52 takes place as a result of a downward pull on the toweling portion 146 which issues through the front wall of the cabinet as shown most clearly in Figure 1. That is, the assemblage is conventional in that a clean toweling supply 148 is disposed within the interior of the cabinet and the toweling 150 issuing therefrom passes upwardly in contact with the feed roll 50, over the pinch roll member 152 and then downwardly through the previously mentioned opening in the forward wall of the cabinet to prevent a continuous loop inasmuch as the soiled toweling 154 passes upwardly through an opening 156 in the bottom wall of the cabinet past the fixed smoothing plate 26 and onto a take-up spool or spindle member 158. The pinch roll 152 is provided with reduced opposite end portions 160 which are received in the inverted L-shaped grooves 162 with the side walls 20 and 22, and the take-up spindle or spool 158 is likewise provided with reduced opposite end portions 164 which are rotatably received in the angulated notches 166 extending from the upper edge of the plates 20 and 22, downwardly and rearwardly therefrom toward the take-up roll member 52. Of course, the toweling 168 which is wrapped about the spool member 158 imparts rotation to the member 158 by virtue of its engagement with the take-up roll 52.

The previously mentioned support rod or bar 28 has rigidly affixed thereto an arcuate guard plate member 170 which overlies a portion of the feed roll member 50 adjacent the take-up roll 52 and serves the purpose of preventing any portion of the soiled toweling 168 from becoming entangled with the feed roll.

In cooperation with the fixed smoothing plate 26 is provided a swingable or movable smoothing plate 172 hingedly mounted between the side walls 20 and 22 by means of pivot bolt member 174 passing therethrough and it will be readily apparent that the hinged smoothing plate normally cooperates with the fixed smoothing plate 26 in a manner to press or smooth the soiled toweling

therebetween prior to its disposition upon the soiled toweling take-up supply 168.

The hinged moving plate 172 is normally held in its position mostly adjacent to the fixed smoothing plate 26 by virtue of the link member 176 and the bell crank member 178. The bell crank is provided with a lower end portion 180 having a laterally projecting ear 182 thereon which projects through an arcuate slot 184 in the side wall 22 to lie behind an end portion of the smoothing plate 172. The bell crank is pivotally secured at substantially its mid-point to the outer surface of the side wall 22 as by a rivet or suitable pivot bolt member 186 and the upper end thereof is pivotally connected as by the element 188 to one end of the link 176.

This end of the link 176 is enlarged as at 190 to project beyond the upper end of the bell crank 178 and be engaged by a resilient spring finger 192 cantilevered on the L-shaped bracket member 194 as by a fastening element 196.

The opposite end of the link 176 projects laterally therefrom through an elongated slot or opening 198 in the side wall 22 and is provided on the opposite side or inner side of the wall 22 with an enlarged head portion 200 of greater dimension than the vertical height of the slot 198 such that this end of the link is guided thereby. The action of the spring finger 192 against the enlarged head portion 190 of the lever 176 is such that in the position shown in the drawings, which is the normal operating position of the hinged smoothing plate and its associated mechanism, the force of the spring 192 against the end 190 of the link is such as to be over-center with relation to the pivot point 186 of the bell crank 178 to resiliently urge the hinged smoothing plate into operative engagement with the fixed smoothing plate 26. However, during loading operation of the dispensing cabinet in which the operator will thread one end of the toweling supply upwardly through the opening 156 in the bottom wall of the cabinet, the operator will swing the hinged smoothing plate 172 rearwardly away from the fixed smoothing plate to a position closely adjacent the rear wall 12 of the cabinet to permit passage of a hand thereby. Consequently, he may reach through the front of the cabinet with his other hand and grasp the free end of the toweling thus threaded to wrap it once or twice about the take-up spindle or spool 158. It would then be difficult for the operator to reposition the hinged smoothing plate 172, but in conventional toweling dispensing assemblies, this is a necessary operation which is frequently neglected through oversight by the operator, so that the toweling is not properly positioned on the take-up spindle 158 during subsequent manipulation of the assembly.

However, the provision of the bell crank 178, the spring 192 and the link 176 makes manual repositioning of the hinged smoothing plate 172 unnecessary inasmuch as it will be readily apparent that when the hinged smoothing plate is in its position closely adjacent the rear wall 12 of the cabinet, the enlarged head 200 of the link 176 will be disposed in the path of movement of the abutment member 66, so that subsequent manipulation of the assembly will effect rearward movement of the link 176 and consequent automatic repositioning of the hinged smoothing plate. In this respect, it is to be noted that when the hinged smoothing plate is in the inoperative or rearwardly swung position, the engagement of the spring finger 192 against the end 190 of the link 176 is such and is so related with respect to the pivot point 186 of the bell crank 178 that an over-center relationship exists whereby the hinged smoothing plate will be positively retained in this position under action of the spring finger 192. Further in this respect, it is to be noted that the abutment member 66 engages the portion 200 of the link 176 for only a short distance of movement of the latter but for a sufficient interval that the link is moved to a position which reverses the over-center relationship ex-

isting when the hinged smoothing plate is in its rearwardly swung position whereby completion of the movement of the hinged plate into an operative engagement with the fixed smoothing plate 26 is effected by the spring finger 192 solely.

Referring now more particularly to Figures 5 and 10, it will be noted that the end cap 118 of the dashpot assembly 106 is provided with a circumferentially extending groove 202 for the purpose of mounting this assembly to permit sufficient movement thereof as required by the manipulation of the lever 78. The forward face of the fixed smoothing plate 26 is provided with a forwardly projecting bracket member 204 provided with a slot to receive the reduced portion of the cap 118 as defined by the groove 202, and a fastener 206 is threaded through the flange 208 of the end cap to project into an enlarged aperture in the bracket 204 to prevent complete withdrawal of the assembly therefrom but to permit sufficient movement between the dashpot 106 and the bracket 204 to allow proper operation of the actuating arm 78.

The purpose of the previously mentioned mounting bar 24 is to removably secured the unit 18 within the cabinet assembly 10 and for this purpose it will be seen that the rear wall 12 of the cabinet is provided with a mounting bracket member 210 which is provided at its upper edge with an offset vertical flange 212 presenting the trough for receiving the mounting bar 24 as shown most clearly in Figure 1. When properly positioned within the cabinet assembly 10, the dispensing unit 18 has its mounting bar 24 engaged with the bracket 210 in the manner shown and rests upon the horizontal shelf or wall 16 of the cabinet along a substantial extent of its lower edge portion. To properly locate the dispensing unit laterally within the cabinet, the forward edge portion of the wall or shelf 16 is provided with an upwardly deformed portion 214 which is just slightly less in width than the distance between the side walls 20 and 22 such that the side walls straddle this deformed portion of the shelf and properly locate the dispensing unit thereby. The lower forward corners of the side walls 20 and 22 are provided with outwardly, laterally projecting latch pin members 216, and latch hook members 218 carried by the shelf 16 are engaged therewith in the manner shown most clearly in Figure 3 to properly hold the dispensing unit 18 in place within the cabinet.

The particular positioning of the dashpot assembly herein shown and described in no way detracts from the available mounting space within the cabinet assembly inasmuch as the dashpot is disposed wholly within the confines of the dispensing unit and is not, as is conventional, disposed outwardly adjacent one side wall of the dispensing unit so as to detract from the over-all usefulness of the dispensing cabinet and assembly. By this particular construction, an associated cabinet can be made smaller and more compact and, moreover, the individual dispensing unit is less susceptible to damage due to mishandling during shipment or the like.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly, all suitable modifications and equivalents may be resorted to, falling within the scope of the appended claims.

What is claimed as new is as follows:

1. In a toweling dispensing unit, a pair of generally rectangular, spaced side walls, a fixed, vertical smoothing plate rigidly interconnecting said side walls adjacent lower rear corners thereof, a feed roll journaled between said side walls adjacent the forward edges thereof, a take-up roll journaled between said side walls rearwardly of said feed roll, means drivingly connecting said rolls, a cam member

rigidly connected to said feed roll adjacent one side wall, said cam member having a helical cam surface, an actuating lever pivotally mounted intermediate its ends to the inner surface of said one side wall and having one end operatively associated with said cam, said cam member including a radial abutment member, said one end of the actuating lever being normally disposed out of the path of movement of said abutment member and movable thereto under influence of said cam surface, and a dashpot mounted on said fixed smoothing plate and connected to the other end of said actuating lever for retarding movement of the actuating lever from a position in the path of movement of said abutment member to its normal position.

2. In a towel dispensing unit, a pair of substantially rectangular, spaced side walls, a fixed, vertical smoothing plate rigidly interconnecting said side walls, a movable smoothing plate hingedly mounted between said side walls and movable between a first position spaced from the fixed smoothing plate and a second position closely adjacent the fixed smoothing plate, an abrasive roll member journaled between said side walls, said roll member being adapted to be rotated as toweling is dispensed from the unit, and stop means periodically arresting rotary movement of said roll member as toweling is dispensed, said stop means including mechanism for urging said movable smoothing plate from its first position to its second position.

3. In a towel dispensing unit, a pair of substantially rectangular, spaced side walls, a fixed, vertical smoothing plate rigidly interconnecting said side walls, a movable smoothing plate hingedly mounted between said side walls and movable between a first position spaced from the fixed smoothing plate and a second position closely adjacent the fixed smoothing plate, an abrasive roll member journaled between said side walls, said roll member being adapted to be rotated as toweling is dispensed from the unit, and stop means periodically arresting rotary movement of said roll member as toweling is dispensed, said stop means including mechanism for urging said movable smoothing plate from its first position to its second position, and a dashpot mounted on the forward face of said fixed smoothing plate.

4. In a towel dispensing unit, a pair of substantially rectangular, spaced side walls, a fixed, vertical smoothing plate rigidly interconnecting said side walls, a movable smoothing plate hingedly mounted between said side walls and movable between a first position spaced from the fixed smoothing plate and a second position closely adjacent the fixed smoothing plate, an abrasive roll member journaled between said side walls, said roll member being adapted to be rotated as toweling is dispensed from the unit, and stop means periodically arresting rotary movement of said roll member as toweling is dispensed, said stop means including mechanism for urging said movable smoothing plate from its first position to its second position, and a dashpot mounted on said fixed smoothing plate.

5. In a towel dispensing unit, a pair of substantially rectangular, spaced side walls, a fixed, vertical smoothing plate rigidly interconnecting said side walls, a movable smoothing plate hingedly mounted between said side walls and movable between a first position spaced from the fixed smoothing plate and a second position closely adjacent the fixed smoothing plate, an abrasive roll member journaled between said side walls, said roll member being adapted to be rotated as toweling is dispensed from the unit, and stop means periodically arresting rotary movement of said roll member as toweling is dispensed, said stop means including a cam element rotatable with said roll member, an

abutment member rigid with said cam element, and a dashpot mounted on said fixed smoothing plate, and a link member engageable by said abutment member for urging said movable smoothing plate from its first position to its second position.

6. In a towel dispensing unit, a pair of substantially rectangular, spaced side walls, a fixed, vertical smoothing plate rigidly interconnecting said side walls, a movable smoothing plate hingedly mounted between said side walls and movable between a first position spaced from the fixed smoothing plate and a second position closely adjacent the fixed smoothing plate, an abrasive roll member journaled between said side walls, said roll member being adapted to be rotated as toweling is dispensed from the unit, and stop means periodically arresting rotary movement of said roll member as toweling is dispensed, said stop means including a cam element rotatable with said roll member, an abutment member rigid with said cam element, and a dashpot mounted on the forward face of said fixed smoothing plate, and a link member engageable by said abutment member for urging said movable smoothing plate from its first position to its second position.

7. In a towel dispensing unit, a pair of substantially rectangular, spaced side walls, a fixed, vertical smoothing plate rigidly interconnecting said side walls, a movable smoothing plate hingedly mounted between said side walls and movable between a first position spaced from the fixed smoothing plate and a second position closely adjacent the fixed smoothing plate, a feed roll journaled between said side walls adjacent the forward edges thereof, a take-up roll journaled between said side walls rearwardly of said feed roll, means drivingly connecting said rolls, and stop means periodically arresting rotary motion of said rolls as toweling is dispensed, said stop means including a cam element rotatable with said roll member, an abutment member rigid with said cam element, and a dashpot mounted on said fixed smoothing plate, and a link member engageable by said abutment member for urging said movable smoothing plate from its first position to its second position.

8. In a towel dispensing unit, a pair of substantially rectangular, spaced side walls, a fixed, vertical smoothing plate rigidly interconnecting said side walls, a movable smoothing plate hingedly mounted between said side walls and movable between a first position spaced from the fixed smoothing plate and a second position closely adjacent the fixed smoothing plate, a feed roll journaled between said side walls adjacent the forward edges thereof, a take-up roll journaled between said side walls rearwardly of said feed roll, means drivingly connecting said rolls, and stop means periodically arresting rotary motion of said rolls as toweling is dispensed, said stop means including a cam element rotatable with said roll member, an abutment member rigid with said cam element, and a dashpot mounted on the forward face of said fixed smoothing plate, and a link member engageable by said abutment member for urging said movable smoothing plate from its first position to its second position.
